Primary Examiner — Ian Simmons*Assistant Examiner* — Khawaja Anwar(74) *Attorney, Agent, or Firm* — Harness, Dickey & Pierce, P.L.C.(57) **CLAIM**

The ornamental design for a lower gripper jaw, as shown and described.

DESCRIPTION

FIG. 1 is a perspective view of a lower gripper jaw in an unclaimed environment showing our new design.

FIG. 2 is a perspective view of the lower gripper jaw removed from the environment.

FIG. 3 is a left side elevation view thereof.

FIG. 4 is a top plan view thereof.

FIG. 5 is a right side elevation view thereof.

FIG. 6 is a rear side elevation view thereof.

FIG. 7 is a bottom plan view thereof; and,

FIG. 8 is a front elevation view thereof.
